DIRECTED BEAM HIGH-FREQUENCY OSCILLATOR

Filed April 28, 1945

UNITED STATES PATENT OFFICE

2,479,084

DIRECTED BEAM HIGH-FREQUENCY
OSCILLATOR

Adolph H. Rosenthal, New York, N. Y., assignor,
by mesne assignments, to Skiatron Corporation,
New York, N. Y., a corporation of New York

Application April 28, 1945, Serial No. 590,823

24 Claims. (Cl. 250—36)

1

This invention relates to an electronic device for producing oscillations of desired frequency, in particular high and ultra-high frequency. It can be used for generating, amplifying, multiplying or indicating (detecting) oscillations of given frequency, and if so desired, for simultaneously changing or modulating the intensity or energy of those oscillations.

The invention particularly concerns electronic devices utilizing transit time phenomena in electron beams or streams produced therein, and it is one of the objects of the invention to increase the output obtainable with such devices.

It is another object of the invention to improve the symmetry at which energy is supplied to a load of devices herein concerned, by velocity modulated electron beams or streams.

It is a particular object of the invention to supply to a tuned or resonating load energy from velocity modulated electron beams or streams during each half-cycle of the oscillations produced by the device in the load.

It is a still further object of the invention to increase the efficiency or figure of merit of arrangements including electronic devices of the type herein concerned, by supplying energy to their load during each half-cycle of the oscillatory energy produced therein and in an essentially symmetrical manner.

It is still another object of the invention to utilize one or more pairs of electron beams or streams for improving the efficiency and increasing the output of electronic devices for the purposes herein concerned, by velocity modulation of those beams or streams and arranging them in such a manner that they supply energy to the load alternately and in useful phase relation to the oscillatory energy to be produced in the load.

These and other objects of the invention will be more clearly understood when the specification proceeds with reference to the drawings in which Fig. 1 illustrates diagrammatically the operation of electro-magnetic devices utilizing transit time phenomena of electron beams and the improvement obtained by the invention, Fig. 2 diagrammatically and partly in top view an arrangement and tube according to the invention with the resonators or lead deleted, Fig. 3 rather schematically a cross section along lines 3—3 in Fig. 2 through the tube and resonator and embodying two modifications of the invention, and Fig. 4 rather schematically a cross section through another embodiment of the invention and diagrammatically one mode of including it in an operation

circuit with certain details omitted which are illustrated in Figs. 2 and 3.

With known electronic devices utilizing transit time phenomena in electron beams, the electrons comprised by the stream or beam continuously emerging from an emitter are grouped recurrently at a distance from the emitter to form concentrated electron charges or bunches in the vicinity of a load circuit or resonator which abstracts energy from the bunches or groups of electrons. On their continued path beyond the grouping or bunching place or phase focus the electrons comprised by the beam or stream de-bunch again and are collected by a suitable electrode. Due to the fact that the stream in which the electrons are thus grouped progresses in one direction only, energy can also be abstracted from or induced by the concentrated charges in one direction only. The load circuit or resonator is tuned to a certain oscillation frequency, and the recurrent grouping of the electrons in the stream passing the load or resonator is timed so that energy is abstracted from a group and translated upon the load so as to add energy to the oscillations therein. In most arrangements such addition is possible; however, only during one half cycle of the oscillation cycle. Usually a narrow gap is formed in the resonator, or preferably loop-like electrodes spaced to form such gap are comprised by the load circuit, and the oscillatory energy in that resonator or load produces an equally oscillating electric field across the gap. During one half-cycle this field is of a direction suited to decelerate electrons of the electron bunch passing therethrough and thereby to abstract energy from them, whereas in the next following half-cycle the direction of the field is inverted and therefore would accelerate the electrons; in the latter case, energy would be abstracted from the oscillations in the load or resonator. Therefore, grouping of the electrons is caused only when that field is of a direction suited to decelerate and thereby abstract energy from an electron group during one half-cycle only of the oscillations in the resonator or load. This is illustrated schematically in Fig. 1, wherein the abscissae represents time and the ordinates represent voltages or currents induced in or translated upon the load or resonator. Since the grouping or bunching effect results in fairly sharp concentrations of the electrons along their path, also short and sharp current pulses 10, 11, 12, 13, etc., are induced in the load circuit or resonator in the same direction within one half cycle of each oscillation period. During the interval

between the pulses no energy is abstracted from the passing electron stream since its electron density is at a minimum. In practice, and due to the fact that the beam current is not absolutely zero between successive groupings, a certain though small amount of oscillatory energy is abstracted from the load by the passing electron beam and by acceleration of its electrons, reconverted into kinetic energy. Thereby, and because only during each second half cycle energy is added to the load circuit, the maximum output of the device is limited and an element of asymmetry introduced in the generation of the oscillations.

According to the invention, a considerable increase and particularly doubling of the output of electronic devices utilizing transit time phenomena in electron beams or streams is obtained and energy supplied to the load circuit or resonator in each half cycle of the oscillation cycle or period. Referring again to Fig. 1, according to the invention energy is supplied not only during the half waves or pulses 10, 11, etc.; in addition thereto and in opposite direction, i. e., at a phase displacement of about 180° with respect to the pulses 10, 11, etc., energy is supplied also during the half waves or pulses 14, 15, 16, etc., indicated by dotted lines.

According to the invention, two streams or beams of electrons are caused to pass closely an energy abstracting portion of the load or resonator, preferably an energy abstracting gap, in essentially opposite directions, and grouping or bunching of the electrons is caused in those beams at a phase displacement approximating 180° or one half cycle. Referring again to Fig. 1, energy will be abstracted from successive electron groups in one beam passing the load in one direction during part of one half cycle of each oscillation period so that voltage half waves or pulses 10, 11, 12, etc., are produced in the load, whereas by the successive electron groups in the other stream of essentially opposite direction voltage half waves or pulses 14, 15, etc., of opposite sign are produced in the same load. The groupings in the two beams are displaced relative to one another in phase at about 180° and the alternation or oscillating electric field across the gap always opposes each electron group passing therethrough so as to decelerate the grouped electrons and abstract energy therefrom. Thereby energy is supplied to the load or resonator during each half cycle of its oscillations, and approximately twice the the energy otherwise supplied to the load by a single grouped beam is produced therein.

According to the invention two electron beams of essentially opposite directions are caused to bunch within the same space wherein a great portion of their kinetic energy is abstracted and which therefore can be regarded as the space or area of the "phase-focus" for both electron beams. For practical reasons it is desirable to produce within that space not only the phase-foci of the two beams, but also to focus them angularly into that space, i. e. to cause a convergence of the two electron streams at this energy abstracting space or area which therefore should be made the locus for four foci, i. e., two phase-foci and two angular foci. Whilst phase-focusing can be obtained as a result of transit time phenomena, angular focusing can be obtained by well known electron-optical means, e. g. substantially imaging the electron emitters or restricted cross sections of the electron beams

in front of the emitters (so-called cross-overs) by electron lens systems upon the space or area of the angular focus. Such electron lens systems may be either purely electro-static and consist e. g. of a number of cylindrical electrodes on suitable D. C. potentials and surrounding each beam, or of magnetic design and consist e. g. of suitably shaped permanent or electro-magnets. Since the decelerated electrons of the beams outgoing from the energy abstracting space or area must be collected, the not yet decelerated electrons of one beam entering that space or area from one side are to be separated from the decelerated electrons outgoing from that space or area in essentially opposite direction. According to the invention, the latter electrons are deflected from the path of the entering electrons and directed to suitable collectors either magnetically or utilizing the difference in average velocity of the incoming and outgoing beams of substantially opposite directions.

Separation by magnetic deflection can be effected by passing the beams through a constant magnetic field which deflects the electrons traversing it in opposite directions clock-wise and anti-clock-wise, respectively. This is illustrated in Figures 2 and 3.

Referring to Figs. 2 and 3, an electron tube is exemplified comprising an evacuated envelope 17, for instance of glass, and electron guns at opposite ends 18, 19. The electron guns comprise, for instance, thermionic electron emitters 20, 21, such as flat cathodes which are heated by heating elements 22, 23 traversed by an adjustable electric heating current from a suitable source (not shown). Electron optical means of any conventional type can be used for concentrating and angularly focusing the electron streams; in this exemplification of the invention and for simplicity's sake, only concentrating elements 24, 25 are shown, usually at the same potential with the emitters 20, 21. The electron streams 26, 27 continuously emerging from the emitters 20, 21 pass through current intensity controlling or modulating fields produced by proper electromagnetic or electrostatic means. Control electrodes or grids 28, 29 are arranged for this purpose in the path of each beam 26, 27 and impress electric signals representative, e. g., of intelligence upon the beam, or modulate its intensity in any impulse frequency other than the carrier or fundamental frequency to be produced or generated. Such signals or impulse frequencies are usually derived from an external source, in particular of alternating voltage, not shown. Steady biasing potentials are applied respectively between electrode 28 and cathode 20, and between electrode 29 and cathode 21, and those biasing potentials are preferably adjustable, either independently or for the same amounts, for instance, by mechanically coupling the handles for adjusting them. If no intensity modulation of the beam or beams by extraneous signals or impulses is intended, electrode 28 and/or 29, or electromagnetic equivalents thereof, can be omitted.

Pairs of grids 30, 31 and 32, 33 or like buncher electrodes are arranged in the paths of electron beams 26 and 27, respectively, for velocity modulation in well known manner of the electrons in the respective beam, and are connected with a source of alternating modulating voltage, not shown, in such a manner that the velocity modulations in beams 26 and 27 are displaced in phase by 180°.

Two pairs of magnetic fields cross the paths

of the oppositely directed beams 26, 27. One pair of fields 34, 35, in a direction perpendicular to the plane of the drawing and into the latter, Fig. 3, is indicated by a "+" sign, and another pair of fluxes 36, 37 in the opposite direction is indicated by a "-" sign within dotted circles, indicating the approximate positions of these fields.

Considering first the effect of those fields upon beam 26 in which the velocities of successive 10 electrons emerging from cathode 20 differ due to their velocity modulation, magnetic flux or field 34 will effect a deflection of all electrons and also an angular resolution of the electrons of different velocities comprised by beam 26. Electrons of 15 lower velocity are angularly deflected to a greater extent than electrons of greater velocity, and consequently fast electrons follow path 38, whereas slow electrons follow path 40; thereby the electrons comprised by beam 26 are somewhat spread. When they pass the second magnetic field 36 of opposite direction, again an angular deflection of electrons of different velocities is effected but in opposite direction than by the first magnetic field 34. The slower electrons are 25 deflected more than the faster ones, and path 38 of the faster electrons is bent to path 42 and path 40 of the slower electrons bent to path 44, whereby the angular resolution of the electrons of different velocities effected by field 34 is fully 30 compensated. By suitable spacing of the magnetic fields 34 and 36 of proper strengths from one another and the velocity-modulating electrodes 30, 31, i. e., by proper dimensioning of the drift 32 path of the electrons, it can be arranged that the slower and faster electrons of beam 26 are angularly and phase-focused to desired extent upon and grouped at the point or area 45 within or in the vicinity of a circumferential gap 46.

Gap 46 is formed between opposite edges 47 of a rotation body 49 forming a cavity resonator arranged outside and as close as possible to envelope 17. The resonance frequency of resonator 49 equals in this case the velocity modulation frequency applied to both beams 26 and 27. The first group or bunch of electrons formed at the point or area 45 will produce by induction a voltage pulse, such as 10, Fig. 1, in the resonator so that oscillations at the frequency of the resonator are set up which produce an alternating electric field of restricted extension across gap 46 and inside tube 17 at the frequency of the oscillations produced in resonator 49. The field across gap 46 will therefore each time be opposed to the direction of flight of an electron grouped in beam 26, accordingly decelerate them and abstract energy from them so that successive voltage pulses 11, 12, 13, etc., Fig. 1, are produced in resonator 49 and build up the oscillatory energy therein.

The thus decelerated outgoing electrons of beam 26 continue their flight in the same direction in which they entered the electric field or area 45, are somewhat de-focused and get out of phase. The fastest ones, though of reduced linear velocity, pass magnetic flux or field 37 of the same direction as field 36, are deflected and their path 44 bent into path 51. The slowest outgoing electrons are deflected to follow path 50. The thus deflected electrons spread somewhat and are finally attracted and collected by electrode 52 at a proper positive potential which can be considerably lower than the accelerating voltage. Electrode 52 is arranged outside and at such distance

from the other electron beam 27 that no substantial deflection or defocusing of the latter results.

The electrons of the oppositely directed beam 27 are velocity modulated by the buncher electrodes or grids 32, 33 in the same way as the electrons of beam 26, the phases of the velocity modulation of the beams 26 and 27 are opposite, however, i. e. displaced at an angle of about 180°. Again the electrons of beam 27 are deflected by the magnetic field 35, the fastest electrons least and their initial path is bent to path 39, whereas as the slowest electrons comprised by beam 27 are deflected most by flux 35 to travel along path 41. The thus somewhat de-focused or spreading beam 27 now passes the magnetic field 37 of opposite direction than field 35 and, therefore, path 41 of its slowest electrons is deflected most to path 44, while path 39 of the fastest electrons is deflected least to path 42. As a result, the spreading of the electrons of different velocities comprised by beam 27 is again compensated and they are focused in point or area 45 essentially to the same at which the electrons of beam 26 had been focused previously. In the same way as described hereinbefore for beam 26, the electrons of different velocities thus angularly focused are also brought in phase focus or concentrated into groups or bunches at area 45. However, due to the phase displacement of about 180° between the velocity modulation of the oppositely directed beams 26, 27, the groupings or bunchings occur in them alternately at place 45 within gap 46 and do not interfere with one another. The direction of the electric field across gap 46 also alternates at the velocity modulation frequency of the beams and in a phase so as to oppose each group of concentrated charges formed in beams 26 and 27 and to abstract alternately energy from them during each half cycle of the oscillations in resonator 49.

Outgoing decelerated electrons of beam 27 pass magnetic field 36, and again fastest electrons, though of decelerated linear velocity are deflected least along path 54 and slowest electrons of reduced linear velocity are deflected most along path 53. A collecting electrode could be arranged in their path the same as electrode 52 in the path of the decelerated outgoing electrons of beam 26. According to a modification of the invention shown in Fig. 3, the decelerated electrons of beam 27, deflected by magnetic field 36, are directed into a neck 55 of tube envelope 17 in which a collector electrode 56 is arranged, preferably at the same positive potential as that of electrode 52. Thereby not only the paths of the incoming electrons of beam 26 and of the outgoing electrons of beam 27 are separated, but any influence of electrode 52 upon beam 26 is eliminated. It should be understood by anyone skilled in the art that the above effects can be secured by proper arrangement of the place where field 36 acts upon the electron beams, and by adjusting its strength.

Different types and arrangements of collecting electrodes 52 and 56 have been shown in Fig. 3 for convenience sake. In practice it will be preferred to use collecting electrodes of equal type, i. e. all of them either of the type 52 or the type 56, or of course of any other suitable type or shape.

Between collector electrodes 52 and 56, on one hand, and electron emitters or cathodes 20, 21 on the other hand, a suitable source of steady potential difference (not shown) is arranged, the

positive side at the collector electrodes and the negative side at the cathodes.

From the above description of the operation of this embodiment of the invention it will be appreciated that the separation of the incoming electrons of one beam on their drift path, from the outgoing decelerated electrons of the other beam is effected by deflecting their paths in different or opposite directions by means of a magnetic field crossing both paths. The degrees of angular resolution exerted upon electrons of different linear velocities of each beam are different, and these electrons are therefore caused to diverge or spread somewhat. While this is not detrimental for outgoing electrons which can be caught by an electrode of sufficiently large surface, it might be undesirable with respect to incoming electrons if they are to be focused sharply in point or area 45. However, the velocity modulated electrons come into phase after their travel over the drift path, and if therefore gap 46 and the restricted electric field crossing it are properly shaped, grouping within that field can be accomplished and utilized even without sharp angular focus, and the magnetic fields 34, 35 can be omitted. In such case, however, electron streams 26, 27 should not be emitted in axial direction and essentially perpendicular to a plane through gap 46, but obliquely to that axis. For instance, the tube extensions containing the electron guns and other electrodes could be arranged in directions of the average beams 38, 40 and 39, 41, respectively. The electrons emerging from the cathode should also in such case be focused by electron optical means upon area 45; upon passing separating field 36 they would be deflected and spread angularly, again the fastest electrons least and the slowest electrons most, and a somewhat defocused and spreading beam rather than a converging beam 42, 44 would travel toward space or area 45 of tube 17 within gap 46. By proper dimensioning of the strength of field 36, of the angle at which velocity modulated electrons enter that field and of their drift path, it can be obtained that the incoming electrons of different linear velocities are grouped and in phase when they pass that area 45 of tube 17. The outgoing decelerated electrons will then enter magnetic field 37 and, due to its identical direction with field 36, be deflected in the same direction once again but to a greater degree because of their reduced linear velocities, toward and finally be attracted by the collector electrode 52. The same, of course, applies to beam 27 flowing in opposite direction in the absence of field 35.

In order to eliminate such spreading and thereby defocusing of the respective beams by the separating magnetic fields 36, 37, the magnetic fields 34, 35 are provided in the respective paths of the two beams with the effects described hereinbefore, viz. to somewhat de-focus each beam before it enters the separating magnetic fields 36, 37 which, because of their opposite direction to fields 35, 36, in addition to their separating action effect angular re-focusing of the respective beam upon area 45. Whereas magnetic fields 36, 37 separate in all events the incoming and outgoing electrons of the oppositely travelling beams, fields 34, 35 compensate the otherwise resulting de-focusing action of the separating fields 36, 37 upon the incoming beams and may therefore be termed compensating fields.

Whether separating deflecting magnetic fields are used only or compensating magnetic fields in addition thereto, it will be appreciated that by the

invention it is obtained that concentrated or grouped electron charges are passing alternately and in opposite direction essentially the same restricted space within the tube in such phases that useful energy can be abstracted from them, and because the frequency of these alternating passages equals that of the tuned load, abstracted energy is added each time to oscillatory power in that load in each half wave of the oscillations.

The compensating and separating fields can be produced at the proper places either by permanent magnets or in the manner exemplified in Fig. 2. Two curved electro-magnet cores 57, 58 are arranged on one side and counter pieces 59, 60 on the opposite side of and with their suitably shaped pole faces as close as possible to envelope 17. Magnetising coils 61, 61 are arranged on cores 57, 58, preferably in series with one another and a source of current 62 and a resistor 63; by moving tap 64 along resistor 63 the magnitude of the exciting current passing coils 61 can be adjusted and thereby the strength of the magnetic fields produced by them. If so desired, pieces 59, 60 can also be provided with magnetizing coils.

Useful oscillatory power can be derived from resonator or load 49 in well known manner, for instance, by loops and concentric conductors 65, 66.

Whereas in the just described embodiment of the invention the two electron beams are separated by deflecting them magnetically in different directions, the embodiment shown in Fig. 4 effects such separation by utilizing the different average velocities of the incoming and outgoing electron beams. Since the outgoing beam upon traversing space or area 45 has translated a great part of its kinetic energy to the oscillating circuit, the average velocity of its electrons is considerably lower than that of the oppositely entering velocity modulated beam. Therefore an electrode of suitably adjusted potential will attract and collect the decelerated electrons of the outgoing beam, while it permits the passage of the electrons of higher average velocity of the incoming beam. In Fig. 4 identical reference numbers indicate identical parts as shown and described hereinbefore with reference to Figs. 2 and 3. Oppositely directed electron streams 26, 27 are emitted by the cathodes 20, 21 heated by proper heating elements 22, 23, concentrated by electrodes 24, 25 and pass control electrodes or grids 28, 29 which control or modulate the intensity of the respective electron stream. The thus intensity modulated streams pass thereafter a pair each of velocity modulating or buncher electrodes or grids 30, 31, and 32, 33, respectively. The thus velocity modulated electron streams pass thereafter electron optical lens systems or beam focusing devices, exemplified by magnetic fields produced by coils 67, 68 provided with casings 69, 70 of iron having narrow cylindrical gaps 71, 72 facing the evacuated envelope 17 of the tube, whereby magnetic fields of proper shape are produced which angularly focus the velocity modulated beams 26, 27 upon a point or area 45 within gap 46 formed between the edges 47, 48 of tank-like resonator 49, as indicated by the dash-dotted line 73, 74 for the electron beams 26, 27, respectively. By this magnetic focusing means the velocity modulated electron streams are converted into focused beams which pass through preferably cylindrical electrodes 75, 76 spacedly surrounding them. Due to their directional qualities resulting from their relatively high

average velocity and focusing, beams 13, 14 are not materially affected by the positive potential of electrodes 15, 16, and group or bunch in point or area 45, provided the spacings between the pairs of buncher electrodes and area 45 is such that the electrons of different velocities in each beam come in phase focus at area or space 45 upon passing the drift path between the respective buncher electrodes and that area or space.

An electric field of comparatively restricted volume is produced across gap 46 in the manner described hereinbefore with reference to Fig. 3, through which the grouped electrons of each focused beam 13, 14 pass within a fraction of a half cycle of the high frequency energy or power produced in resonator or load 49 at such instants that this electric field opposes the grouped electrons of the respective beam, and thereby decelerates and abstracts energy from them. The outgoing electrons of beam 13 of now relatively small velocities will diverge or spread somewhat along the paths 71 by the action of electrode 76 which attracts and collects them. Similarly the outgoing decelerated electrons of beam 14 will diverge or spread behind area 45 along paths 78 and be attracted and collected by electrode 75. The collector electrodes 75 and 76 not only collect the decelerated outgoing electrons but can also exert in cooperation with the other electrodes, such as cathodes 20, 21 and concentrating electrodes 24, 25, an angular focusing action upon the velocity-modulated electrons of the incoming beams.

In order to secure the effects described, it is required for this embodiment of the invention in the same way as for the one previously described with reference to Fig. 3, that grouping of the electrons occurs in the beams 13, 14 at a phase displacement of about 180°. Since the current density or charge intensity in each stream or beam is a minimum between successive groupings of the electrons, it will be appreciated that the successive charge concentrations or groupings in space or area 45 of the electrons comprised by beam 13 as well as their deceleration occur while the current density or charge intensity in beam 14 passing space 45 is at a minimum, and vice versa, resulting in practically negligible interference between the oppositely directed beams 13, 14. The same holds, of course, for the embodiment of the invention exemplified in Fig. 3.

In order to bring about this 180° phase displacement between the velocity modulations of the two streams 26, 27 which pass area 45 in counterflow, the respective pairs of buncher electrodes are to be driven by sufficiently high alternating voltages at the same modulation frequency but at opposite phases. To this effect, any suitable source of high frequency can be used. In the exemplification of Fig. 4, a Lecher system is used comprising two parallel conductors or wires 79, 80. Buncher electrode 31 nearest to cathode 20 and buncher electrode 33 remotest from cathode 21 are connected, preferably in adjustable manner at 81, 82, with wire 80, whereas buncher electrode 30 remotest from cathode 20 and buncher electrode 32 nearest to cathode 21 are connected, preferably in adjustable manner at 83, 84, with wire 79. If points 81 and 82, as well as points 83 and 84 are spaced for instance by a wave length and therefore of equal oscillation phase, velocity modulations of same frequency but in phase-opposition are secured of the oppositely directed electron streams

26, 27 emanating from emitters 20 and 21, respectively. If the spacings of points 81 and 82, as well as of points 83 and 84 equals for instance a half wave length, the same result can be obtained e. g. by reversing the connections 81, 83 of electrodes 30, 31 with the conductors 80, 79.

Resonator 49 is tuned in this example to the velocity modulation frequency, and a small fraction of the oscillatory energy or power produced in the resonator is branched off by the loop and concentric conductor or lead 65 and translated in a preferably adjustable manner at 85 upon wire 79; the conductive wall of resonator 49 is connected by means of lead 86 with wire 80, preferably in adjustable manner at 87. A hollow wave guide can be used instead of the Lecher system.

A source of steady current 88 is arranged between the cathodes 20, 21 and the first beam concentrating electrodes 24, 25, on the one hand, and collector electrodes 75, 76 on the other hand. The positive terminal of source 88 is connected by conductors 89, 90 with the collecting electrodes, whereas its negative terminal is connected by conductors 91, 92 and 93 with the respective cathodes and concentrating electrodes. It is understood by anybody skilled in the art that the positive potential of the collector electrodes can be lower than that of accelerating electrodes, if used; thereby heat and other losses in collecting the decelerated electrons are considerably reduced.

Another source of current 94, for instance direct current, heating the heating elements 22, 23 of the cathodes, is connected with the former by conductors 95, 96 and 97, 98, respectively. A further source of steady potential (not shown) is arranged between the cathodes 20, 21 and the Lecher system, and thereby the velocity-modulating electrodes 30, 31, 32 and 33; it may be supplied by source 88 by connecting e. g. point 86 with a suitable part of source 88 directly or through a potentiometer. Conventional means for adjusting that heating current are not shown.

If mere generation of oscillatory high frequency or ultra-high frequency power is intended, the control electrodes 28, 29 can be used for adjusting the constant power of those oscillations by means of a suitable biasing potential applied to those electrodes. A small fraction of the oscillatory power produced in load 49 is fed back through the Lecher system, and thereby self-maintained oscillations are produced; useful energy can be derived from load 49, e. g., through a concentric conductor 66.

If mere high frequency amplification is intended of incoming oscillatory energy of a frequency, e. g. modulated frequency the same as that to which load 49 is tuned, the feed back connection shown can be omitted. The incoming energy is fed to the Lecher system 79, 80 driving the buncher electrodes, and amplified energy is derived from load 49 through lead 66, or in any other manner known in the art.

If a modulation is desired of the high frequency power produced or generated by the above arrangements, which requires intensity modulation or control of the electron streams emanating from the emitters 20, 21, the modulating or control voltages are impressed upon the control electrodes 28, 29 or their equivalents arranged in those streams. Impulses representative of any intelligence or magnitude whatsoever, the source of which is indicated schematically at 99, are translated upon the streams by connecting one terminal of that source through conductors 100, 101

with the respective control electrodes 28, 29. The other terminal of that source of modulating impulses is adjustably connected through tap 102 with a potentiometer 103 across a source of steady current 104. Another potentiometer 105 is arranged across source 104 and adjustably connected through tap 106 with conductor 93 which leads to emitter 20 and is also connected through conductor 92 with emitter 21. By properly adjusting taps 102, 106 on the respective potentiometers, any desired positive or negative bias can be given the control electrodes 28, 29 with respect to the emitters or cathodes 20, 21. Television, telephone, telegraph or other signals or impulses can be impressed upon the high frequency or ultra-high frequency power or carrier wave produced in load 49.

Detection or rectification of those signals or impulses can be combined with their amplification, e. g. by utilizing the collector current between leads 89, 90 and the positive terminal of source 88.

By the use of a resonator 49 of a resonance frequency equalling a higher harmonic of the frequency in which the electron streams are velocity modulated, the device can be used as frequency multiplier. In this case a (primary) high frequency oscillation, which may be intensity modulated by a signal, is impressed upon the velocity modulation electrodes 30, 31, and 32, 33. The sharp voltage peaks as illustrated in Fig. 1 are, because of their sharpness, rich in high harmonics which can excite in resonator 49 strong oscillations in its resonance frequency equalling such higher harmonic. The thus generated (secondary) oscillations of a frequency equalling a multiple of the frequency impressed upon the modulating electrodes, are also modulated in intensity by signals impressed upon the (primary) oscillations, and these intensity modulations will in general also be amplified; thus the double effect of an amplifier and a frequency multiplier can be obtained.

It should be understood that the arrangements shown by way of exemplification in Fig. 4 for driving the buncher electrodes, generating, amplifying or modulating high or ultra-high frequency oscillations, etc., can be used for similar purposes in the embodiment shown in Fig. 3.

The resonator 49 is shown in the embodiments of the invention for simplicity's sake as a rotation body which may have, for instance, the particular shape of a known "rhumbatron," such as a doughnut shape. Any other closed tank oscillator or tuned circuit can be used instead, and any other type of high frequency or ultra-high frequency circuit substituted, such as a Lecher system, hollow wave guide system, open radiator dipole, etc., as shown and described in more detail in my co-pending application Serial No. 519,130, filed January 21, 1944, now U. S. Patent No. 2,454,094. Such circuit is suitably connected with or includes annular electrodes which are spaced from one another so as to form a gap 46 and are arranged outside or inside envelope 17 so that electric energy can be translated by the grouped electrons upon the electrodes in passing e. g. a decelerating electric field across that gap, by induction, or otherwise. Annular or hollow electrodes 107 substituted for rotation body or resonator 49 and arranged, e. g., inside tube 17 are indicated in dotted lines in Fig. 4; they are to be connected in conventional (and therefore not shown) manner with or form part of a tuned load circuit usually outside the tube.

The above described embodiments of the invention are of optimum effect if a 180° phase displacement between the velocity modulations of the oppositely directed electron streams is established by the essentially symmetrical arrangement of the various operative elements with respect to gap 46, so as to obtain charge concentrations alternately travelling in opposite directions through the space within gap 46 or equivalent energy abstracting means. Any asymmetry in the two drift paths can be compensated by adjusting the phases of the oscillations driving the velocity modulating electrodes 30, 31 and 32, 33 of any suitable and known type so as to obtain a substantially 180° phase displacement between the successive groups or bunches in the two electron streams within space 45. For instance, if the pairs of buncher electrodes in each stream are driven at the same frequency and phase, an asymmetric arrangement could be used and the lengths of the drift paths over which the velocity modulated electrons of the streams travel made different so that the transit time of the velocity modulated electrons for instance in stream 27 exceeds that of the velocity modulated electrons in stream 26 for an interval equalling a half period; the recurrent groupings of the electrons in stream 27 will then lag behind those in stream 26 by a half period or at a 180° phase displacement. Thereby again the essentially symmetrical push-pull action according to the invention is obtained by electron groups alternately passing in opposite direction the energy abstracting field space or means.

It should be understood that the invention is not limited to any exemplification hereinbefore described and shown in the drawing but is to be derived in its broadest aspects from the appended claims.

What I claim is:

1. A method of producing electric oscillations, particularly of high or ultra-high frequency, including the steps of developing two streams of electrons, modulating periodically the velocities of the electrons in each stream so that they group in the progressing streams, directing successively in opposite directions an electron group formed in one stream and an electron group formed in the other stream through a restricted space common to both electron streams wherein energy is abstracted from said electrons and their linear velocities are reduced, utilizing the successively abstracted energies for producing electric oscillations, and collecting said decelerated electrons of each stream outside the path of the other stream and outside said space.

2. A method of producing electric oscillations, particularly of high frequency, including the steps of developing two electron streams, velocity modulating both streams at the same frequency and at a phase displacement of about 180° so that electrons of different velocities in each stream come alternately into phase at the end of their drift path, directing successively and in opposite direction electrons of essentially same phase at the end of their drift paths in said streams, through a restricted space common to both electron streams wherein energy is abstracted from them and their velocities are reduced, utilizing the successively abstracted energies for producing electric oscillations, and collecting decelerated electrons of each beam outside the path of the other beam and outside said space.

3. A method of producing electric oscillations, particularly high frequency oscillations, includ-

ing the steps of directing alternately and in opposite direction the electron groups formed in two velocity modulated electron streams through a restricted space common to both electron streams wherein energy is abstracted from each group and the electrons comprised thereby are decelerated, utilizing the successively abstracted energies for producing electric oscillations of a frequency related to that of the alternating energy abstractions, and collecting said decelerated electrons of each stream outside the path of the other stream and outside said space.

4. A method of producing electric oscillations, particularly high or ultra-high oscillations, including the steps of developing two electron streams, velocity modulating both streams at the same frequency to provide recurrent groups of electrons in each progressing stream, angularly focusing said groups on to substantially the same restricted space common to both electron streams wherein energy can be abstracted from said groups passing therethrough and the electrons comprised by them are decelerated, directing said groups in one focused beam through said space in opposite direction to that of said groups in the other focused beam and at a phase displacement of about 180° between successive groups passing said space, collecting said decelerated electrons of each beam outgoing from said space separately outside the path of the other beam and outside said space, and utilizing the energies abstracted successively from said groups for producing oscillatory energy at the frequency of said successive abstractions.

5. A method of producing electric oscillations, particularly high or ultra-high frequency oscillations, including the steps of developing two electron streams, velocity modulating both streams at the same frequency so that groups of electrons recur in each progressing stream at said frequency, focusing each velocity modulated stream before said grouping occurs therein and thereafter directing it spacedly from and past a region of positive potential so that both streams at the place where said grouping occurs in them are focused and directed in opposite directions through a restricted space common to both electron streams wherein energy is abstracted from each incoming group and its electrons are decelerated, timing the recurrence of said focused groups in both streams so that an incoming group of one stream alternates with an incoming group of the other stream, utilizing the successively abstracted energies for producing oscillatory electric energy, and collecting the decelerated electrons of one stream outgoing from said space outside the path of the incoming other stream and outside said space.

6. A method of producing electric oscillations, particularly high or ultra-high frequency oscillations, including the steps of developing two high velocity electron streams, velocity modulating both streams at the same frequency so that groups of electrons recur in each progressing stream at said frequency, focusing each velocity modulated stream before said grouping occurs therein and thereafter directing it spacedly from and past a region of positive potential which concentrates the passing electrons of relatively high velocities so that both streams at the place where said grouping occurs in them are focused onto but enter in opposite direction a restricted space common to both electron streams wherein energy is abstracted from each incoming group and its electrons are considerably decelerated, timing the

recurrence of said focused groups in both streams so that an incoming group of one stream alternates with an incoming group of the other stream, utilizing the successively abstracted energies for producing oscillatory electric energy, and deflecting electrostatically and collecting the electrons of relatively low velocities of a stream outgoing from said space outside the path of the incoming other stream and outside said space.

7. A method of producing electric oscillations, particularly high or ultra-high frequency oscillations, including the steps of developing two electron beams, velocity modulating both beams at the same frequency so that the electrons group recurrently in each progressing beam at said frequency, directing said beams from opposite sides through a restricted space common to both electron streams so that said groupings occur therein, timing the velocity modulations of said beams so that their recurrent groupings alternate, abstracting within said space energy from each group and thereby decelerating its electrons, separating on each side of said space the electrons of an outgoing beam from those of an oppositely incoming beam by passing them through a magnetic field which deflects the outgoing electrons from the path of the incoming electrons, and collecting the thus deflected outgoing electrons outside the path of the incoming other stream and outside said space.

8. A method of producing electric oscillations, particularly high or ultra-high frequency oscillations, including the steps of developing two electron streams, velocity modulating both streams at the same frequency so that electron groups recur in the progressing streams at said frequency, focusing and directing said streams from opposite sides into a restricted space so that said groupings occur therein, timing the velocity modulations of said streams so that their recurrent groupings alternate, abstracting within said space energy from each group and thereby decelerating its electrons, separating on each side of said space the electrons of an outgoing stream from those of an oppositely incoming stream by passing them through a separating magnetic field which deflects the outgoing electrons from the path of the incoming electrons, collecting the thus deflected outgoing electrons, and passing the electrons of an incoming focused stream through a compensating magnetic field of opposite direction than and preceding said separating field, so as to de-focus said incoming stream by said compensating field and re-focus it by said separating field onto said space.

9. A method for producing electric oscillations, particularly of high or ultra-high frequency, including the steps of developing two electron streams, velocity modulating both streams at the same frequency so that groups of electrons recur in each progressing stream at said frequency but after different transit times, directing the groups in one stream opposite those in the other stream through a restricted space common to both electron streams wherein energy is abstracted from each passing group and its electrons are decelerated, phasing the velocity modulations in said streams relative to one another so that the groups in said streams pass alternately and at a phase displacement of about 180° said restricted space, utilizing said abstracted energies for producing electric oscillatory energy, and collecting the decelerated electrons of each stream outside the path of the other stream and outside said space.

10. A method for producing electric oscilla-

tions, particularly of high or ultra-high frequency, including the steps of developing two electron streams, velocity modulating both streams at the same frequency so that groups of electrons recur in each progressing stream at said frequency, directing the groups in one stream opposite those in the other stream through a restricted space common to both electron streams wherein energy is abstracted from each passing group and its electrons are decelerated, phasing the velocity modulations in said streams relative to one another so that the groups in said streams pass alternately and at a phase displacement of about 180° said restricted space, utilizing said abstracted energies for producing electric oscillations, and collecting the decelerated electrons of each stream outside the path of the other stream and outside said space.

11. A method as set forth in claim 1, including the step of changing the intensity of at least one of said electron streams prior to its velocity modulation.

12. An electronic device for producing electric oscillations, particularly of high or ultra-high frequency, including an evacuated envelope, means for developing two electron streams in said envelope, means for velocity modulating each stream so that groups of electrons recur in each progressing stream, electron optical means for directing said streams from opposite sides through a restricted space common to both electron streams within said envelope so that said groups in each stream form in said space, energy abstracting means arranged close to said space outside the paths of said streams and groups forming therein, electrical means for driving said velocity modulating means at the same frequency and at such phase relation that said groups form alternately in said streams within said space, and electrodes outside said space and the paths of said streams toward said space for collecting the electrons of each stream outgoing from said space.

13. An electronic device and system for producing electric oscillations, particularly of high and ultra-high frequency, said device including an evacuated envelope, means for developing two electron streams in said envelope, means for velocity modulating each stream so that groups of electrons recur in each progressing stream at relatively high average velocity, electron optical means for directing said streams from opposite sides and focusing them through a restricted space common to both electron streams within said envelope so that said groups in each stream form in said space, energy abstracting means arranged close to said space outside the paths of said streams and groups forming therein, and electrodes on position potential within said envelope outside the path of each incoming focused stream arranged between said electron optical means and energy abstracting means for deflecting electrostatically and collecting the electrons of the opposite stream of relatively low average velocity outgoing from said space; said system including electrical means for driving said velocity modulating means at the same frequency and at such phase relation that said groups form alternately in said streams within said space.

14. An electronic device and system for producing electric oscillations, particularly of high and ultra-high frequency, said device including an evacuated envelope, means for developing two electron streams in said envelope, means for velocity modulating each stream so that groups

of electrons recur in each progressing stream, electron optical means for directing said streams from opposite sides and focusing them into a restricted space within said envelope so that said groups in each stream form in said space, energy abstracting means arranged close to said space outside the paths of said streams and groups forming therein, means for producing a magnetic field each at opposite sides of said restricted space crossing the paths of a stream each incoming and outgoing from said space so as to deflect the electrons of the outgoing stream from the path of the incoming stream, and electrodes within said envelope in the path of each thus deflected outgoing stream for collecting its electrons; said system including electrical means for driving said velocity modulating means at the same frequency and at such phase relation that said groups form alternately in said streams within said space.

15. An electronic device as set forth in claim 14, in which said collecting electrodes are spacedly arranged from the path of an incoming stream between said magnetic field and said velocity modulating means.

16. An electronic device as set forth in claim 14, in which said collecting electrodes are arranged within a neck-like extension of said envelope.

17. An electronic device and system for producing electric oscillations, particularly of high and ultra-high frequency, said device including an elongated evacuated envelope, means for developing two electron streams in said envelope and close to opposite ends thereof, means for velocity modulating each stream so that groups of electrons recur in each progressing stream, electron optical means for directing said streams from opposite sides into a restricted space within said envelope so that said groups in each stream form in said space, a pair of energy abstracting electrodes spacedly arranged from one another so as to form a gap between them substantially determining said restricted space, means at opposite sides of said space for producing a separating magnetic field each across the paths of the electron streams incoming and outgoing from said space so as to deflect the electrons of the outgoing stream from the path of the incoming stream, means for producing another magnetic field across the path of each incoming stream between said separating magnetic field and said velocity modulating means, the direction of said other field opposite that of said separating field so that the electrons of different velocities of the incoming stream are de-focused and deflected in one direction by said other field and re-focused and deflected in opposite direction by said separating field, and electrodes in the path of each deflected outgoing stream for collecting its electrons; said system including electrical means for driving said velocity modulating means at the same frequency and at such phase relation that said groups form alternately in said streams within said space.

18. A system as set forth in claim 17, in which the magnetic fields of opposite direction at each side of said space are produced by means of a common electromagnet the opposite fluxes of which cross said envelope and are closed through a magnetizable counter-piece at the opposite side of said envelope.

19. An electronic device as set forth in claim 12, including a hollow conductive body forming a cavity resonator of a frequency related to that

of said velocity modulations, said body provided with a gap the edges of which lie in substantially parallel spaced planes essentially perpendicular to the direction of the opposite electron streams and determine substantially said restricted space.

20. An electronic device for producing electric oscillations, particularly of high and ultra-high frequency, including an elongated evacuated envelope, an electron gun each close to the opposite ends of and within said envelope so as to develop electron streams of opposite direction, buncher electrodes in the path of each electron stream adapted to be driven so as to cause alternate bunching of the electrons in said streams within a restricted space about in the middle of said envelope, means for focusing each stream and groups forming therein into said space, a pair of energy abstracting annular electrodes spaced-ly arranged from one another so as to form a gap between them substantially determining said space, and a collecting electrode each in the path of a stream outgoing from said space and spaced from the path of a stream incoming to said space.

21. An electronic device as set forth in claim 12, including means for changing the intensity of at least one of said electron streams emerging from an electron gun and arranged between said gun and said velocity modulating means.

22. An electronic device as set forth in claim 12,

in which said means for developing, velocity modulating and directing said streams and said collecting electrodes are arranged substantially symmetrically with respect to said restricted space.

5 23. An electronic device as set forth in claim 14, in which said means for developing, velocity modulating and directing said streams and said magnetic means and said collecting electrodes are arranged substantially symmetrically with respect to said restricted space.

10 24. An electronic device as set forth in claim 17, in which said means for developing, velocity modulating and directing said streams and said energy abstracting electrodes and said collecting electrodes and said separating magnetic means are arranged substantially symmetrically with respect to said gap.
